DESIGN FOR A COMBINED DESK AND DRESSER CABINET

John T. Li Mandri, New York, N. Y.

Application April 4, 1933, Serial No. 47,688

Term of patent 14 years

To all whom it may concern:

Be it known that I, JOHN T. LI MANDRI, a citizen of the United States, residing at New York city, county, and State of New York, have invented a new, original, and ornamental Design for a Combined Desk and Dresser Cabinet, of which the following is a specification, reference being had to the accompanying drawing, forming a part hereof.

In the drawing, Fig. 1 is a perspective view of the article, showing the desk slide extended on one side of the cabinet, it being also extendable on the opposite side, and Fig. 2 is a side view thereof on a reduced scale.

I claim:—

The ornamental design for a combined desk and dresser cabinet as shown and described.

JOHN T. LI MANDRI.

CERTIFICATE OF CORRECTION
